UNITED STATES PATENT OFFICE.

UMBERTO MIOZZA, OF WASHINGTON, DISTRICT OF COLUMBIA.

WEDGE ATTACHMENT FOR SHOES.

Application filed January 13, 1926. Serial No. 81,036.

This invention relates to improvements in wedge attachments for use within shoes and upon the outer sides of the insoles of a shoe to prevent the foot of a person from sliding 5 within the shoe, whereby the latter may not become disfigured nor will the heels run over.

Another object of the invention resides in the provision of a removably secured and 10 slidably mounted auxiliary wedge positioned upon the outer side of the wedge attachment to give the desired rise and fall to the foot of the wearer.

With the above and other objects in view, the invention further consists of the following 15 novel features and details of construction, to be hereinafter more fully described, illustrated in the accompanying drawing, and pointed out in the appended claim.

20 In the drawing:—

Figure 1 is a fragmentary top plan view of a shoe, illustrating the arrangement and manner by means of which the invention is used in conjunction therewith.

25 Figure 2 is a bottom plan view of the invention per se.

Figure 3 is a perspective view of the invention.

Figure 4 is a transverse sectional view 30 taken on line 4—4 of Figure 1.

Figure 5 is a horizontal sectional view taken on line 5—5 of Figure 3.

Figure 6 is a perspective view of the sliding wedge.

35 Referring to the drawing in detail, wherein like characters of reference denote corresponding parts, the reference character 10 indicates a shoe sole, 11 an insole and 12 the shoe upper, all of which being of the usual 40 and well known construction incident to that of shoe construction.

The invention resides in the provision of an elongated strip 13, preferably composed of leather, having one end curved, as indicated at 14, to conform to the curvature of the heel portion of the shoe. The outer side edge of the strip 13 is shaped to resemble and correspond to the particular shape of the innerside of the shoe upper 12 as best 50 illustrated in Figure 1 of the drawing. A wear plate 15 is carried upon the innerside edge and underside of the strip 13, as clearly illustrated in Figure 2 of the drawing. The elongated strip 13 tapers outwardly from its 55 inner side edge and includes front and rear pockets 16 and 17.

A wedge 18, preferably composed of leather, is positioned within the pocket 16 and adapted for longitudinal sliding movement therein. Said wedge is furthermore 60 tapered outwardly from the inner side edge thereof, which is preferably arcuate-shaped as substantiated from the dotted line positions in Figures 1 and 3 of the drawing. A stud 19, upstanding from the upper side of the wedge 18 is adapted to project within an elongated guide slot 20 provided in the upper side of the strip 13. The wedge 18 may be regulated by longitudinal sliding movement and set in a desired position within 70 the pocket 16 commensurate with the configuration and size of a person's foot.

A wedge 21, also composed of leather, is positioned within the rear pocket 17 in the strip 13. The wedge 21 may be made any 75 thickness to elevate the particular heel to occupy a desired height and to prevent the foot from riding outwardly within a shoe.

From the foregoing it is apparent that the 80 invention will obviate the usual tendency of a person's foot to ride outwardly within a shoe to disfigure the same upon one side thereof as well as the adjacent side of the heel.

The invention is susceptible of various 85 changes in its form, proportions and minor details of construction, and the right is herein reserved to make such changes as properly fall within the scope of the appended claim.

90 Having thus described the invention, what is claimed is:—

A wedge attachment adapted for use within shoes comprising an elongated strip 95 adapted to conform to the configuration of the side edge of a shoe, said strip being horizontally and inwardly tapered from the outer marginal edges thereof and which includes spaced forward and rear pockets in the thicker outermost side edge, the forward 100 pocket communicating with an elongated slot in the upper side of the strip, a wedge carried within the forward pocket, a companion wedge carried within the rear pocket, and an elongated stud upstanding from the first mentioned wedge, extended within the elongated slot and cooperating therewith to permit longitudinal adjustment of the wedge to longitudinally regulate the thickness of the strip.

105 In testimony whereof I affix my signature.
UMBERTO MIOZZA.
